FIG. 1 is a front elevation view of the first embodiment of the venetian shutter,

FIG. 2 is a right side view, which is simultaneously a left side view of the first embodiment thereof,

FIG. 3 is a top plan view of the first embodiment thereof,

FIG. 4 is a bottom view of the first embodiment thereof,

FIG. 5 is a rear elevation view of the first embodiment thereof,

FIG. 6 is a cross-sectional view along with the line VI—VI in FIG. 1,

FIG. 7 is a cross-sectional view along with the line VII—VII in FIG. 1,

FIG. 8 is a perspective view of the first embodiment thereof,

FIG. 9 is a perspective view of the second embodiment of the venetian shutter,

FIG. 10 is an enlarged fragmentary perspective view of the second embodiment thereof;

FIG. 11 is a perspective view of the third embodiment of the venetian shutter with the frame omitted;

FIG. 12 is an enlarged fragmentary sectional view of the third embodiment thereof; and,

FIG. 13 is an enlarged perspective view of a shutter unit composing the venetian shutter illustrated in FIG. 11.

I claim:

The ornamental design for a venetian shutter, as shown.
